Primary Examiner — Derrick Holland*Assistant Examiner* — Lauren Calve(74) *Attorney, Agent, or Firm* — Bracewell & Giuliani LLP(57) **CLAIM**

I claim the ornamental design for a cam member, as shown and described.

DESCRIPTION

FIG. 1 is a perspective view of a cam member of my invention;

FIG. 2 is a front elevation view of the cam member of FIG. 1; FIG. 3 is rear elevation view of the cam member of FIG. 1; FIG. 4 is a top plan view of the cam member of FIG. 1; and, FIG. 5 is a side-elevation view of the cam member of FIG. 1. The broken lines shown represent indeterminate length and form no part of the claimed design.
